UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922. Serial No. 543,650.

This invention pertains to improvements in lubricating apparatus.

It is among the objects of the invention to provide lubricating apparatus in which a source of lubricant under pressure may be coupled to and uncoupled from a lubricant-receiving part while minimizing the loss of lubricant.

In the drawings, which show an illustrative embodiment of a preferred form of my invention:

Fig. 1 is a side elevation of a lubricant gun coupled to a lubricant-receiving element;

Fig. 2 is a longitudinal central section through the discharge end of the gun illustrated in Fig. 1, being partly in elevation and showing the lubricant-receiving part in elevation;

Fig. 3 is a section on the line 3—3 of Fig. 2, showing the parts in uncoupled relation, the valve being locked closed;

Fig. 4 is a section on the line 3—3 of Fig. 2, showing the parts in coupled relation, the valve being opened and the parts locked against uncoupling;

Fig. 5 is an end elevation of the valve-operating ring;

Fig. 6 includes a side and end elevation of the coupling nozzle;

Fig. 7 includes a side and end elevation of the interior coupling sleeve;

Fig. 8 includes a side and end elevation of the sealing part, which preferably acts also as a valve part;

Fig. 9 is an end elevation of a cooperating valve part;

Fig. 10 is a section on the line 10—10 of Fig. 7; and

Fig. 11 is a longitudinal section illustrating the relative positions longitudinally of the parts shown in Fig. 3.

Referring to the drawings and to the preferred form of my invention illustrated, I have shown a lubricant-expelling device typified by the barrel 12 having the usual rear head 13 into which is threaded the usual plunger-carrying stem 14.

The discharge end of the device or gun is provided with a coupling including a nozzle part 15 adapted to be readily coupled to and uncoupled from a lubricant-receiving nipple 16 which may be of the type illustrated

in my co-pending application Serial No. 543,643, filed herewith March 14, 1922.

In the preferred form of coupling illustrated, the nozzle 15 is provided with an end opening 17 (Fig. 6) adapted to admit the end of the nipple 16 including the projections 18 thereon, and to provide flanges 19 adapted to underlie said projections when the nozzle 15 is turned relative to the nipple 16. Within the nozzle 15, I have provided a sleeve 20 (Figs. 2 and 7) presenting an opening 21 shaped similarly to the opening 17 in the nozzle 15, and positioned to lie against the sides of the projections 18 of the nipple 16. The sleeve 20 may turn a limited extent relative to the nozzle 15 to permit coupling of the parts. In the preferred form of my invention illustrated, I have provided valve mechanism controlling discharge of lubricant to the nipple 16 and have coordinated the coupling and valve operating mechanism to preclude opening of the valve until coupling is completed and also preferably, as illustrated, to preclude uncoupling until the closing of the valve is effected. To this end, the sealing part 22,

presenting lubricant passages or ports 30, 31 and carrying the sealing washer 23, is rotatably mounted in part within the sleeve 20 and a valve part 32 presenting ports 33, 34 is provided to cooperate with the ports 30, 31. In the form of my invention illustrated, the valve opening movement is actuated by turning a ring 35 connected by a screw 36 to the sealing part 22, and clutch means is provided opposing turning of the ring 35 to open the valve until the nozzle 15 and sleeve 20 are in the relative position in which the coupling is completed. When the ring 35 is turned to such position as to open the valve, clutch means also preclude turning of the sleeve 20 relative to the nozzle to effect uncoupling until after the ring 35 is turned to valve closing position.

Assuming the parts to be in coupled relation and the valve open, as shown in Fig. 2, the ring 35, nozzle 15, sleeve 22 and sealing part 20 will occupy the relative position shown in Fig. 4, relative rotation between the sleeve 20 and nozzle 15 being precluded by clutch means, herein taking the form of a ball 40 entered in a hole 41 in the nozzle 15 and pressed into a depres-

sion 42 in the sleeve 20 by the inside wall of the ring 35—thus precluding uncoupling. If the ring be now turned to close the valve, the depression 43 will come opposite the ball 40 permitting it to come out of the depression 42 in the sleeve, thereby permitting relative rotation between the nozzle 15 and sleeve 20 during uncoupling from the nipple 16. The uncoupling movement will bring the parts to the position shown in Figs. 3 and 11, in which the ball 40 is held by the outside wall of the sleeve 20 in position precluding opening of the valve by turning of the ring 35 relative to the nozzle 15 until coupling is again effected. This interlock is best shown in Fig. 3. The slot 50 in the sleeve 22 which cooperates with the nozzle-carried pin 51 to limit rotation between nozzle 15 and sleeve 20 appears as viewed in Fig. 3 to interfere with the last-described interlock, but does not do so because out of line with the hole 41 as shown in Fig. 11. The use of the apparatus described is simple; the nozzle being introduced over the cylindrical portion 60 of the nipple 16 is turned until the projections 18 of the nipple permit the desired entrance of the nipple into the nozzle. The apertures of the nozzle 15 and the sleeve 20 are now aligned to permit entrance of the nipple. When entered, a slight turn of the barrel of the gun causes the nozzle to turn therewith while the sleeve 20 remains stationary with the nipple. When the pin 51 reaches the end of slot 50, coupling is completed and the clutch means is in position so that the ring 35 may be turned to open the valve by turning the sealing part 22 without corresponding turning of the valve part 32 which is held against rotation by a projection 70 (Fig. 9) entering a hole 71 in the nozzle (Fig. 6), the valve part preferably pressed toward its seat by the spring 72. Lubricant passing through the ports 30, 31, 33, 34 will now pass to the lubricant-receiving nipple, incidentally getting behind the sealing washer 23 and pressing this tightly against the face of the nipple 16 surrounding the lubricant-receiving aperture therein. Should the operator carelessly try to uncouple without first closing the valve, he cannot do so because of the interlock between the coupling parts shown in Fig. 4. Pursuant to closing of the valve, uncoupling may be effected by counter-clockwise turning of the barrel of the gun. Should the operator carelessly try to open the valve while thus uncoupled, he cannot do so because of the interlock shown in Figs. 3 and 11. Leakage between the sealing part 22 and the nozzle is precluded by the pressure of the lubricant and spring 72 pressing the taper flange 80 against its seat.

While I have shown and described a preferred form of one embodiment of my in-

vention, it will be understood that changes involving omission, substitution, alteration and reversal of parts, and even changes in the mode of operation, may be made without departing from the scope of my invention, which is best defined in the following claims.

I claim:

1. Lubricating apparatus of the class described including a lubricant-delivering compressor having at its discharge end a quick detachable coupling for connection by movement of said compressor relative to a lubricant-receiving element, said coupling providing a rotary valve, and clutch means positively opposing opening of said valve until completion of the coupling operation, said valve operable by a manipulative operation separate and distinct from the coupling operation.

2. A lubricating apparatus including a lubricant-delivering compressor having at its discharge end a coupling for connection by movement of said compressor relative to a lubricant-receiving element, said coupling providing a valve, a sealing part, and clutch means opposing opening of said valve until completion of the coupling operation and opposing uncoupling of said delivering compressor from said receiving element until completion of the valve-closing operation, said valve operable by a manipulative operation separate and distinct from the coupling operation, whereby said sealing part is turned relative to the coupling to open said valve.

3. Lubricating apparatus comprising a barrel, a lubricant-expelling plunger therein, a discharge nozzle having a coupling and a rotary valve associated therewith, said coupling operable by turning of the grease gun barrel relative to a lubricant-receiving nipple introduced in said nozzle and said valve operable by an independent manual turning movement of an associated part coaxial with the coupling.

4. Lubricating apparatus comprising a lubricant-expelling device including a discharge nozzle having a terminal portion with flanges to engage beneath lateral projections on a lubricant receiving element when the lubricant-receiving element is entered in said terminal portion and one is turned relative to the other, a perforated part within said nozzle for delivering lubricant to the lubricant-receiving element, and a second perforated part having independent handle means, said perforated parts cooperating therewith to provide a rotary disc valve controlling discharge of lubricant from said nozzle independent of the lubricant-receiving element.

In testimony whereof, I have signed my name to this specification.

HOWARD J. MURPHY.
